UNITED STATES PATENT OFFICE.

JOHN A. BELL, OF LACON, ILLINOIS.

IMPROVEMENT IN SAFETY-POCKETS.

Specification forming part of Letters Patent No. 57,072, dated August 14, 1866.

To all whom it may concern:

Be it known that I, JOHN A. BELL, of Lacon, Marshall county, Illinois, have invented a new and useful Pocket-Safe; and I do hereby declare the following to be a full, clear, and exact description thereof, reference being had to the accompanying drawings, making part of this specification.

My invention relates to a device called by me the "pocket-safe," for attachment to the lining of a pocket, the same being provided with an elastic loop for the reception and retention of a porte-monnaie or pocket-book.

Figure 1 represents the device before attachment to the pocket. Fig. 2 represents the same secured to its place within the pocket. Fig. 3 shows a modification in the manner of applying the elastic cord hereinafter described.

A is an elastic thong or strap, which thong is provided with buttons *a*, and occupies eyelets *B B'* on a plate, C, having a shank or pin, D, which, being passed through the pocket-lining, has its extreme end clinched over a notch, *c*, in the end of the plate C, as shown in Fig. 2.

While it is easy, by extending the thong A, to insert the pocket-book or other object de-

sired to be secured, yet such thong will resist any clandestine or violent attempt to remove the article, at least sufficiently to give the wearer warning of the robbery.

Although describing a specific form, I do not propose to confine myself thereto, as various modifications are obviously possible—for example, the thong may consist of an endless ring, and the point of the pin may be caught in a hook on the plate, after the manner of brooches and breastpins.

I am aware that an elastic band or cord has before been used to secure articles within a pocket; but

I claim and desire to secure by Letters Patent—

The clasp or pin D, in the described combination with the bar C and elastic thong A, to admit of the latter being readily applied to the garment or detached therefrom at the will of the user.

In testimony of which invention I hereunto set my hand.

JOHN A. BELL.
